(57) **CLAIM**

(22) Filed: **Mar. 19, 2009**

The ornamental design for a pull tab of slider for slide fastener, as shown and described.

(30) **Foreign Application Priority Data**

Nov. 5, 2008 (JP) 2008-028402

DESCRIPTION

(51) **LOC (9) Cl.** **02-07**

FIG. 1 is a perspective view of the front, bottom and right side of a pull tab of slider for slide fastener showing our new design;

(52) **U.S. Cl.** **D11/221**

FIG. 2 is front view thereof;

(58) **Field of Classification Search** D11/79-85,
D11/94-116, 200, 201, 221; 24/381-383,
24/385-387, 414-417, 421-422, 427-431,
24/433

FIG. 3 is a rear view thereof;

See application file for complete search history.

FIG. 4 is a right side view thereof, the left side view being mirror image thereof;

(56) **References Cited**

FIG. 5 is a top plan view thereof;

U.S. PATENT DOCUMENTS

FIG. 6 is a bottom view thereof; and,

2,474,372 A * 6/1949 Schmitt 24/578.15

FIG. 7 is a reference view of usage thereof.

The portion of the article in broken lines are shown for illustrative purposes only and form no part of the claimed design.
